UNITED STATES PATENT OFFICE.

FRANK A. BASCOM, OF GREENVILLE, PENNSYLVANIA.

SASH-FASTENER.

SPECIFICATION forming part of Letters Patent No. 396,386, dated January 22, 1889.

Application filed February 25, 1888. Serial No. 265,334. (No model.)

To all whom it may concern:

Be it known that I, FRANK A. BASCOM, a citizen of the United States, residing at Greenville, in the county of Mercer and State of Pennsylvania, have invented certain new and useful Improvements in Sash-Fasteners; and I do hereby declare the following to be a full, clear, and exact description of the invention, such as will enable others skilled in the art to 10 which it appertains to make and use the same.

My invention relates to improvements in that class of sash fasteners and supporters in which a sector actuates a wedge by means of a lever; and the object of my invention is to 15 produce a sash fastener and supporter which is very simple in its construction, not liable to get out of order, and reliable in its operation; also, to actuate a roughened wedge in such manner that it can be arranged to prevent the raising of the window-sash by force, especially from the outside; also, to produce a very strong device that will not be easily broken; furthermore, to furnish a sash fastener and supporter that can be readily applied to old window-sashes now in use, as well 20 as to new ones, and without defacing the sash or frame, and, finally, to produce a very inexpensive device which will not disfigure the appearance of the window sash or frame.

With these objects in view my invention 25 consists in the construction of certain details and arrangement of parts, as will be more fully described hereinafter, and specifically pointed out in the claims, reference being had 30 to the accompanying drawings and the letters of reference marked thereon.

Like letters indicate similar parts in the different figures of the drawings, in which—

Figure 1 represents a side elevation of my 40 sash-fastener. Fig. 2 is a front view of the same. Fig. 3 is a side view, with half of the housing removed to expose the interior parts in a raised position. Fig. 4 is a front, rear, and side view of the wedge. Figs. 5, 6, and 7 are detail views of the sector and actuating-lever. Figs. 8, 9, and 10 are detail views of 45 the housing. Fig. 11 is a detail view of a modified wedge and lever.

In the drawings, A represents the housing 50 or casing, which is, for convenience, made in two parts riveted together by suitable rivets.

In this housing a wedge, B, provided on its face with points *b* and on its rear side with a depression, *c*, and a series of short cogs or teeth, *d*, is placed and is free to move up and down. With said teeth *d* a sector, C, journaled in bearings *f*, secured or cast to the sides of the housing and having a double set of teeth, *e*, engages. On one side the journal projects through the housing, and is preferably flattened, or it may be squared, as at *g*, to which the actuating-lever D is secured and prevents it from turning. The wedge B is provided at its upper corners with short projections or ears *h*, which engage with the slots 60 E in the sides of the housing. The slots are made of such shape as to permit the wedge in its movement up and down to accommodate itself to the radius of the sector C. The teeth on the sector are divided by a partition, *i*, and said teeth are staggered, so that the teeth on one side of the partition are placed opposite to the spaces on the other side. By arranging the teeth in this manner there will be no jarring, or what is technically called 65 "backlash," and it causes a steady sliding motion of the wedge. This wedge is provided with flanges *k*, which move in guides *l*, formed in the sides of the housing and serve to steady 70 it in its sliding motion.

If desired, the face of the wedge may be serrated or roughened in any other suitable manner, so as to prevent slipping or sliding of the window-sash. The lever is preferably constructed in such manner that it will automatically descend by gravity, thus forming a gravitating or weighted lever. Any suitable material may be employed in the manufacture of the device, and it may be made plain or ornamental. The rattling of windows is 80 also prevented by my device, and the device forms an automatic lock in windows with weights and cords.

The operation is as follows: The device being first connected with the teeth of the sector meshing with those on the wedge, and the parts of the housing riveted together, the device is secured in position in the window-frame. If it is desired to raise the window-sash, the actuating-lever is raised and with it 90 the wedge, which permits the sash to be moved up and down until the lever is released, which 95

causes the points on the wedge to engage with the side of the frame and hold the sash in any position. To reverse the device will prevent raising of the sash from the outside by force by placing it in the window-sash.

Having thus described my invention, what I claim is—

1. In a sash-fastener, the combination of a housing with a sector mounted therein, a wedge guided in slots in said housing, and a gravitating lever for operating the same, substantially as specified.
2. The combination of a bisected housing having slots therein with the wedge seated in said slots and provided with teeth on its rear side, a sector, also provided with teeth to engage the teeth of the wedge, and a gravitating lever for operating the same, substantially as and for the purpose set forth.
3. In a sash-fastener, the combination of the

housing with the sector C, having a double set of teeth, the wedge B, having a double set of teeth on the back thereof, said teeth being adapted to engage the teeth of the sector, and a gravitating lever, substantially as set forth.

4. The housing A, provided with slots E and guides l, in combination with the wedge B, having lugs h, flanges k, to engage with said slots and guides, and provided with teeth b, a double sector meshing with the teeth of said wedge, and a gravitating lever, D, connected therewith, substantially as and for the purpose set forth.

In testimony whereof I hereby affix my signature in presence of two witnesses.

FRANK A. BASCOM.
